UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A DROP-HANGER FOR JOURNAL-BOXES.

SPECIFICATION forming part of Design No. 32,926, dated July 10, 1900.

Application filed March 19, 1900. Serial No. 9,339. Term of patent 14 years.

To all whom it may concern:

Be it known that I, ANTONIO C. PESSANO, of the city and county of Philadelphia, in the State of Pennsylvania, have invented a new and original Design for a Drop-Hanger for Journal-Boxes, of which the following is a specification.

My new and original design for drop-hangers for journal-boxes is shown in the accompanying drawings, in which—

Figure 1 is a front elevation of a hanger embodying the design, and Fig. 2 is a side elevation of the same.

AA are two depending arms curved throughout their length and inclining toward each other at the bottom, said arms terminating at their upper ends in flat flange portions *a a*, united by a transverse flat web B. The lower ends of the arms AA are united by a straight cross-piece d, and a second cross-piece b connects the arms at a distance from the ends, so as to form an opening N in the lower portion of the hanger, having straight top and bottom boundaries connected by inwardly-curved sides, the width of the opening at the bottom being less than the width at the top. The cross-pieces b d respectively carry bosses g i, arranged in line with one another. The opposite and outer faces of the lower portions of the arms AA have longitudinal enlarged rounded ribs H H, terminating at their lower ends in flattened heads h h. The upper portions of these rounded ribs H H are enlarged by bulbous portions P and provided immediately above said enlargements with small bosses M M, through which are small circular

holes m m, opening horizontally through said bosses and arms. The flattened portions *a a* at the upper ends of the arms AA are made flat between said arms and carry bosses K K, immediately adjoining the outside of said arms. A centrally-disposed rib f, of less height than the bosses M or the enlarged rounded ribs H H, extends along the outer and inner faces of the arms AA. Similar narrow ribs f extend across the top and bottom faces of the cross-piece b and the top face of the bottom cross-piece d.

The essential features of the design are the depending arms AA, curved throughout their length and united by the cross-pieces b d, forming between said cross-pieces and the arms an opening straight at top and bottom with inwardly-curved sides and of less width at the bottom than at the top, the arms being also provided with enlarged longitudinal ribs H H on the outer faces of their lower portions, which ribs terminate at their upper ends in bulbous enlargements P and bosses M, having circular holes m through them.

What I claim as new, and desire to secure by Letters Patent, is as follows:

The design for a drop-hanger for journal-boxes substantially as described and as shown in the accompanying drawings.

In testimony of which invention I have hereunto set my hand.

ANTONIO C. PESSANO.
